CLAIM

I claim the ornamental design for a cup, as shown and described.

DESCRIPTION

FIG. 1 is an upper perspective view of an embodiment of the cup;

FIG. 2 is a lower perspective view of the cup;

FIG. 3 is a side view of the cup, with the opposite side being a mirror image thereof;

FIG. 4 is a top view of the cup; and,

FIG. 5 is a bottom view of the cup.
